UNITED STATES PATENT OFFICE.

ABRAM L. McFARLAND, OF PALATKA, FLORIDA.

TRACK-LAYING MACHINE.

SPECIFICATION forming part of Letters Patent No. 333,770, dated January 5, 1886.

Application filed July 6, 1885. Serial No. 170,728. (No model.)

To all whom it may concern:

Be it known that I, ABRAM L. McFARLAND, of Palatka, in the county of Putnam and State of Florida, have invented new and 5 useful Improvements in Machines for Laying Railroad-Tracks; and I do hereby declare that the following is a full and accurate description of the same.

My invention relates to that class of machines for laying railroad-tracks wherein the ties and rails are by mechanical means transferred from the cars of the train to the road-bed in front of the train, where they are put in position and secured by hand, and the 15 train advanced as fast as the panels of track are completed, and it avoids several defects incident to the mechanisms heretofore employed.

Formerly a car was employed having upon 20 it a motor-engine and an endless-chain carrier, now commonly called a "tramway," extending from the rear end of the car to a distance of thirty feet, or more, beyond the front end of said car. The ties and rails 25 loaded upon flat cars immediately in rear of said machine-car are successively placed on said carrier, and thereby delivered to the workmen on the road-bed in front of said machine, by whom the ties and rails are placed 30 and secured. The machine-car and the transportation-cars behind it are then pushed forward upon the newly-made panel of track and the operation repeated. In this way all 35 the material for the way is transported to the front upon the track itself, instead of being hauled by horses and distributed along the line of the roadway at greatly-increased labor and expense; but the carrier of the machine above described only extends to the rear end 40 of the machine-car, and the material loaded upon the flat cars of the transportation-train must therefore be conveyed forward to the flat car next to the machine-car. To avoid the labor of this transportation, inclined 45 tramways have been placed along the sides of the cars and extending the whole length of the train. These side projecting tramways are necessarily removed while the train is running back and forth, because they are constantly liable to suffer damage themselves, or 50 inflict damage to structure along the line, such as bridges, stations, &c. The necessity

of frequent removal and replacement of the tramways has been avoided by placing a tramway along the center of the deck of the flat 55 car; and by combining a number of cars so provided to constitute the construction train; but whereas the side tramways could be applied to any cars at hand the central tramway, being fixed to the car, required the employment 60 only of cars so specially provided.

My invention remedies the defects and methods of the machines alluded to above by the following instrumentalities: First, portable tramways are provided, each being about 65 half the length of a flat car, and they are successively placed in position as the load is discharged, so as to lengthen the tramway as required and permit the employment of ordinary flat cars; second, the portable tramways 70 are each provided with a proper length of open-link drag-chain, and as each tramway is added the endless drag-chain is unhooked and the tramway chain is added, so that the endless drag-chain is extended in length 75 each time a tramway is added, and may be extended to the whole length of the train; third, the forward extension of the carrier is supported by a crane-frame on the machine-car, and said machine-car is provided 80 with three tramways, the center one extending about thirty feet in front of the machine-car, to deliver ties beyond the panel of track next in front of said machine, and those at the sides terminating at the front of said car, to 85 deliver the rails; fourth, two tackles traveling on truss-rods on each side of said crane-frame take and support the rails as they leave the carrier, and enable the workmen to lower them simultaneously exactly in the place desired without lifting; fifth, an endless chain 90 passes from the extreme front of the carrier to the rear extremity of the tramway, and is provided with dogs or hooks which engage the ties or rails and positively pull them forward along the tramway; sixth, inclined chutes or aprons are placed in advance of two or more rollers adjacent to the ends of the tramway, to guide the ends of the advancing tie upon the rollers, as set forth.

In the accompanying drawings, Figure 1 is a side elevation of my machine-car. Fig. 2 is a plan of the same. Fig. 3 is a cross-sectional elevation of the same. Fig. 4 is a side eleva-

- tion of two flat cars, showing the operation of the tramways. Fig. 5 is a front elevation of the portable tramway and trestle enlarged. Fig. 6 represents the chain and dog attached. Fig. 7 is a sectional elevation showing the tramway roller and apron. Fig. 8 is a perspective view of my machine and train, showing the operation.
- 2 is the road-bed.
 10 3 are the ties.
 4 4 are the rails in place on the road.
 5 5 are ties in position on the road-bed, ready to receive the rails.
 6 6 are ties moving forward on the carrier.
 15 7 7 are ties still on the car.
 8 8 are rails ready to be lowered upon the ties.
 9 9 are rails still on the car.
 10 is the machine-car, constructed like an ordinary flat car, and mounted upon ordinary trucks, 11. At the front end of said car there are two crane posts, 12, supported at the top by guys or string-braces 14, which extend to the rear end of the car and are secured there.
 25 The tops of posts 12 are united by cross-bar 15. Two braces, 13, extend from the rear end of the car to points beneath the crane-posts, about twelve inches above the track, where they are supported by tension-rods 38 at each 30 side. A crane or spar, 16, is seated on the end of the brace 13, and extends upward and forward to a point about twenty-five feet in advance of the car 10, and a cross-bar, 17, unites the forward ends of the spars 16. String- 35 pieces or guys 18 connect the forward ends of the crane 16 with the tops of the posts 12. This structure constitutes a crane-frame extending forward from the car 10. The tramway is in two parts, 19 and 20, the former 40 projecting over the roadway, and at its front end suspended from the crane 16, and the part 20 is mounted permanently on the car 10. The two parts are jointed together at their adjoining ends, so that the front end of the carrier 45 19 may be raised or lowered, as desired. The engine 21 is also mounted on the car 10, and power is transmitted from it, by belt or otherwise, to the driving-pulley 22, whereby motion is transmitted to the endless chain 23, 50 which going in one direction traverses the tramway-rollers 24, and going in the other direction swings from guide-pulley 25. At the rear end of the car 10 there is a gallows-frame, 26, having guide-pulleys 27 at the top for the chain 23 to pass over. Between said pulleys 27 a slack-take-up weight, 28, is suspended on the chain 23, to keep it taut. The chain 23 is provided at intervals of about eight feet with dogs 29, each provided with a spur to drive 55 60 into a tie, and thus make a positive engagement with the tie to pull it forcibly forward. 30 30 are truss or traveler rods extending from the cross-bar 15 to the cross-bar 17, to tie said bars and assist in supporting the crane 65 16. Traveling blocks and tackles 31 31 are mounted on said rods and adapted to slide back and forth thereon. When the front end

of a rail presents itself at the front end of the car, it is attached to one of the tackles 31, and thereby supported as said tackle passes along 70 said truss-rod 30. As the rear end of the rail approaches the front end of the car, it is attached to said rear end, and the rail is then wholly supported by the crane. When the ties are laid and the roadway is ready for 75 the rails, the workmen simply disengage said tackles and lower the rails in place.

It is not undesirable that the endless carrier which moves the ties shall be elevated above the floor of the car, because the ties are piled 80 high; but it is different with regard to the rails, which, being heavy, always occupy position close to the floor. It is desirable, also, that the iron shall pass down each side of the machine and be simultaneously delivered close 85 to the proper locality where they are to be secured. I therefore provide two tramways, 32 32—one on each side of 20 and at a lower level—for the conveyance of rails, which may also be drawn forward by chains, or by hand, as preferred. Two rails may thereby be simultaneously advanced and placed, and without being lifted and carried by the workmen. This is a material saving in time and labor. The three tramways 20 32 32 are all constructed on one 90 set of trestle, 33 33, and those on the car 10 are permanently fixed, but those for the ordinary flat cars, 34, are made entirely portable, and are provided with spurs 45, to penetrate and catch in the floor of the car to keep them in place. 100 The three-part tramways are, however, only required for those flat cars which may be loaded with rails; for those cars which are loaded with ties, only a single tramway on trestle, 105 as 35. Each of said portable tramways is provided with an elevated guide-pulley, 36, at one end and a length of chain, 23, sufficient to pass twice the length of the tramway-section. This chain is preferably made with separable links capable of being separated at any point, so 110 that when an additional tramway-section is added the endless drive-chain is opened and the chain belonging to the added section is inserted, and so the endless chain may be lengthened to any extent, the take-up weight 115 28 sufficing to keep the chain always taut. These portable tramways, being on the car, 120 present no difficulty in running the train past the structures ordinarily along the line. They are light, and add nothing appreciable to the load. Therefore they may be carried back and forth, or may be left at the front during each trip to the material-yard. If carried back and forth, the trainmen uncouple the chains and disconnect the sections during the 125 time the train is going to the material-yard. The cars are loaded in the usual way, and the trestles deposited on top of the load during the return-trip to the front.

Adjoining cars nearly always stand at 130 slightly different heights, and sometimes this difference amounts to six or eight inches. A tie passing from the tramway of one car to that of another on a different level will not

move in line with the rollers on the tramway which it is approaching, but will pitch down upon them in one case, or require to be lifted up in the other case. To obviate the possible 5 resulting stoppage in such case, I place an inclined chute or apron, 37, in advance of each of two or three rollers adjacent to the end of the tramway, and whether the tie is advancing on a higher or lower level its end will be 10 received upon one or the other of said aprons and conducted upward to the top of the roller.

Having described my invention, I claim—

1. The combination, with the machine and transportation cars of a track-laying train, of 15 the portable tramways provided with level-footed trestles and adapted to be set along the flat floor of the cars as fast as they are unloaded, and thus gradually extended from the front to the rear end of the train.
2. The combination, with the machine-car provided with an engine and an open-link endless-chain carrier extending from the rear end to the point in advance of said car, and one or more transportation cars, constituting 25 a track-laying train, of portable tramways each provided with trestles and a sufficient length of chain, whereby said tramway may, as required, be added on and the endless chain extended by inserting additional lengths of 30 chain, as set forth.
3. The portable tramway provided with rollers 24, and trestles provided with spurs in the feet, guide-rollers, and chains, substantially as set forth.
4. The tramway for track-laying machines, provided with three sets of rollers, the central set elevated above the side, as set forth. 35

5. The combination of the machine-car 10, provided with the forwardly-extending crane 16, the tramway-carrier 19, suspended therefrom, the carrier 20 and 32, mounted permanently on said car, and the endless-chain driver 23, substantially as set forth. 40

6. The combination, with the machine-car 10, provided with the crane 16 and tramways 45 32, of the truss-rods on either side of the tramway, and traveling tackles running thereon, whereby the rails are seized and supported after leaving the tramway and independently delivered upon the ties at both sides of the 50 way, as set forth.

7. The machine-car 10, provided with an engine, an endless-chain carrier, a gallows-frame, and slack take-up 28.

8. The combination, with a track-laying machine-car and a tramway mounted thereon, of 55 an overhead endless carrier-chain provided with hooks or dogs, whereby the ties may be positively engaged and forcibly pulled along said tramway. 60

9. The combination, with the several cars constituting a track-laying train, of tramways, each provided with tramway-rollers, and inclined chutes or aprons in advance of two or more rollers adjacent to the ends of the tramway, to guide the ties upon the rollers, as set 65 forth.

A. L. McFARLAND.
